UNITED STATES PATENT OFFICE.

HAROLD P. BLUM, OF CLEVELAND, OHIO, ASSIGNOR TO THE CLEVELAND RAILWAY SUPPLY COMPANY, OF CLEVELAND, OHIO, A CORPORATION OF OHIO.

TRoughLESS SKELETON FLANGE-WAY GUARD.

Application filed August 4, 1926. Serial No. 127,076.

The present invention relates to flange way guards for highway crossings and the like and more particularly to the constructional features which provide for proper 5 positioning on the ties and for providing a guard which can be easily and properly packed with paving material. Essentially the present guard is a sectional rail provided with a full length base member and provided 10 with vertical supports for the guard proper and also having the necessary spaces to hold the guard properly spaced away from the rail. The base is provided with spike notches so that the guard may be held 15 against lateral as well as vertical and longitudinal movement. To the accomplishment of the foregoing and related ends, said invention, then consists of the means herein- 20 after fully described and particularly pointed out in the claims.

The accompanying drawing and the following description set forth in detail certain mechanism embodying the invention, such disclosed means constituting, however, but 25 one of various mechanical forms in which the principle of the invention may be used.

In said accompanying drawing:

Fig. 1 is a side elevation of an assembled guard showing one of the joints in section; 30 Fig. 2 is a top plan view of a single section; Fig. 3 is a sectional view taken on the line 3—3 of Fig. 2 and showing the main rail in dotted lines; Fig. 4 is an end view of the guard taken from the left of Fig. 2; 35 and Fig. 5 is an end view of the other end of one section.

The present flange way guard is a sectional guard, each section consisting of a continuous base member 1 having spaced 40 pairs of spike notches 2 so that the guard may be easily secured to the ties, the continuous base making uneven tie spacing an unimportant factor as a sufficient number of notches will be over ties to afford satisfactory 45 holding means. Extending upwardly from the base are a series of spaced legs 3, which are formed integrally with the base, and which are likewise integral with the flange-way guard rail 4. Likewise formed in- 50 integrally with the rail 4 and legs 3 are spacing members 5 having a trough shaped upper contour 6, the ends of the members being adapted to have a wedge fit between the ball 7 and the base 12 of the main rail 8 as best 55 shown in Fig. 3. To strengthen the entire

structure which is thus of skeleton design, integral webs 9 are formed between the base member and the legs 3; there are also stiffening webs 10.

The flange way rail proper is cut away at 60 the back side but extends at a slope on the rail side to form the desired trough contour with the spacers. At one end the flange way is provided with an enlarged boss 15 having a tapering socket 16 while at the other end a 65 similar boss 17 is employed which terminates in a tapered pin 18 adapted to be forced into tight engagement in the socket of the adjacent section as shown in section in Fig. 1, this interengagement between sec- 70 tions maintaining the sections in alignment and also preventing excessive vertical movement.

The wide spaces between vertical legs 3 and the open spaces between the spacers 5 75 allow paving material to be readily and easily packed in and around the flange way guard and rail to make a smooth crossing, the upper edges of the spacers acting as forms so that the material may be shaped 80 to a trough of the desired contour between the main rail and the guard. The small openings 20 at the top of the legs allow the paving material to be filled in underneath the flange way rail for the substantially entire length and thus form a unitary 85 structure without divisions for the entire crossing length. The use of a flange way guard which has a downwardly extending sloping flange and a horizontal top portion 90 also aids in making a proper bond between the paving material and the flangeway guard.

Other modes of applying the principle of my invention may be employed instead of 95 the one explained, change being made as regards the mechanism herein disclosed, provided the means stated by any of the following claims or the equivalent of such stated means be employed.

I therefore particularly point out and distinctly claim as my invention:

1. A flange way guard section of skeleton type, comprising a continuous base member for engagement and attachment to the ties, a series of spaced vertical legs formed integrally with said base, a flange way guard member formed integrally with said legs and adapted to lie parallel with the main rail, and a series of inwardly extending 105 110

spacer members formed integrally with said legs and guard, and adapted for wedging engagement between the ball and the base flange of the main rail and having a trough shaped upper contour.

2. A flange way guard section of skeleton type, comprising a continuous base member for engagement and attachment to the ties, a series of spaced vertical legs formed integrally with said base, a flange way guard member formed integrally with said legs and adapted to lie parallel with the main rail, and a series of inwardly extending spacer members formed integrally with said legs and guard, and adapted for wedging engagement between the ball and the base flange of the main rail and having a trough shaped upper contour, said base member being provided with spaced pairs of spike receiving notches.

3. A flange way guard section of skeleton type, comprising a continuous base member for engagement and attachment to the ties, a series of spaced vertical legs formed integrally with said base, a flange way guard member formed integrally with said legs and adapted to lie parallel with the main rail, and a series of inwardly extending spacer members formed integrally with said legs and guard, and adapted for wedging engagement between the ball and the base flange of the main rail and having a trough shaped upper contour, said guard member having a horizontal top flange and an inwardly sloping downwardly extending flange.

4. A flange way guard section of skeleton type, comprising a continuous base member for engagement and attachment to the ties, a series of spaced vertical legs formed integrally with said base, a flange way guard member formed integrally with said legs, and a series of inwardly extending spacer members formed integrally with said legs and guard, and adapted for engagement with the main rail and having a trough shaped upper contour, said guard member being provided at one end with a tapered hole and at the other end with a tapered pin for interlocking engagements with adjacent sections.

5. A flange way guard section of skeleton type, comprising a continuous base member for engagement and attachment to the ties, a series of spaced vertical legs formed integrally with said base, a flange way guard

member formed integrally with said legs, and a series of inwardly extending spacer members formed integrally with said legs and guard, and adapted for engagement with the main rail and having a trough shaped upper contour, said guard member having a horizontal top flange and an inwardly sloping downwardly extending flange and being provided at one end with a tapered hole and at the other end with a tapered pin for interlocking engagements with adjacent sections.

6. A flange way guard section of skeleton type, comprising a continuous base member for engagement and attachment to the ties, a series of spaced vertical legs formed integrally with said base, a flange way guard member formed integrally with said legs, and a series of inwardly extending spacer members formed integrally with said legs and guard, and adapted for engagement with the main rail and having a trough shaped upper contour, said guard member having a horizontal top flange and an inwardly sloping downwardly extending flange, said spacer members forming a smooth face with the downwardly extending flange of said guard member to form a trough pattern for filling with paving material.

7. A flange way guard section of skeleton type, comprising a continuous base member for engagement and attachment to the ties, a series of spaced vertical legs formed integrally with said base, a flange way guard member formed integrally with said legs, and a series of inwardly extending spacer members formed integrally with said legs and guard, and adapted for engagement with the main rail and having a trough shaped upper contour, said guard member having a horizontal top flange and an inwardly sloping downwardly extending flange and being provided at one end with a tapered hole and at the other end with a tapered pin for interlocking engagements with adjacent sections, such openings between legs and under said horizontal flange of said guard member being adapted to be filled with paving material and said spacing members being adapted to form a trough pattern for such material between said flange way guard and the main rail.

Signed by me this 2nd day of August, 110
1926.

HAROLD P. BLUM.
